SPRING CUSHION UNIT AND METHOD OF
MAKING

George A. Stackhouse, Oakland, Calif., assignor
to L. A. Young Spring and Wire Corporation,
Detroit, Mich.

Application November 18, 1935, Serial No. 50,303

2 Claims. (Cl. 5—353)

This invention relates to improvements in spring cushion units and method of making.

The main objects of this invention are:

First, to provide a spring cushion unit or structure which is well adapted as a filler for mattresses, pillows and cushions or of spring units or toppers for seat cushions, automobile upholstery and the like.

Second, to provide a structure having these advantages which is provided with a base or foundation padding for the upholstery, this padding being effectively secured to the filler unit so that it is not likely to be displaced in assembling the unit in the completed structure or in use.

Third, to provide a structure in which the springs are individually supported and pocketed, at the same time a structure which is very economical in material and assembly.

Fourth, to provide a structure of the pocketed spring type in which springs of relatively large diameter relative to their height may be used.

Fifth, to provide a method of producing spring units having these advantages.

Objects relating to details and economies of my invention will appear from the description to follow. The invention is defined and pointed out in the claims.

Preferred embodiments of my invention are illustrated in the accompanying drawings, in which:

Fig. 1 is a fragmentary plan view of a cushion unit embodying the features of my invention, a portion of the upper wall and of the padding being removed to better illustrate the construction and relation of parts.

Fig. 2 is an enlarged detail section on line 2—2 of Fig. 1, the springs being indicated in full lines, certain of the parts being shown conventionally, no attempt being made to section the fabric or the padding.

Fig. 3 is a fragmentary plan view of one of the pocket units.

Fig. 4 is a fragmentary plan view of a modified form of pocket unit, the modification being in the connecting tape or strip for the pocket members.

Fig. 5 is a fragmentary perspective view of one of the pocket members.

Fig. 6 is a diagrammatic view of the preferred form or method of stitching.

Fig. 7 is a fragmentary conventionalized perspective view of one of the casing walls with the padding thereon.

Fig. 8 is an enlarged detail view illustrating

the preferred method of preliminary attachment of the padding to the wall fabric.

Fig. 9 is a fragmentary plan view of a modified form or embodiment of my invention in which wire staples or stitches are employed in lieu of the threads of the sewing machine stitching.

Fig. 10 is an enlarged detail section on a line corresponding to line 10—10 of Fig. 9.

Fig. 11 is an enlarged detail view on a line corresponding to line 11—11 of Fig. 10.

My improved spring cushion as illustrated in the accompanying drawings comprises top and bottom walls 1 and 2, the edges of which are turned inwardly and stitched together at 3 to provide the side walls 4 of the casing. It will be understood that top and bottom are here used as a matter of convenience in description in both the specification and claims as the structure is the same on both sides and may be used either side up. In the preferred embodiment illustrated these walls are formed of burlap which is found to be suitable in strength and also has a relatively coarse mesh which facilitates the preliminary attachment of the padding 5 thereto. This padding 5 is preferably of sisal although other fibrous material may be used, tufts of sisal indicated at 6 being drawn through the burlap—that is, drawn between strands thereof at suitably spaced intervals thus effecting a preliminary attachment of the padding to the casing walls so that they may be conveniently handled in the assembling operations.

I provide a plurality of pocket units, each consisting of pocket members 7 also preferably formed of burlap, the ends of the pocket members being folded upon themselves and secured by stitching 8. This greatly adds to the strength of the pocket members and prevents their raveling or pulling out when attached to the side walls 40 as will be hereinafter described. These pocket members are secured together in series by means of a longitudinal strap or tape 9 which, in the preferred embodiment, is also a strip of burlap, this being secured by the longitudinal row of 45 stitches 10. In the embodiment illustrated in Fig. 4, the longitudinal strip is in the form of a tape 11 secured, however, by the row of longitudinal stitches 10. This connecting of the pocket members performs a double function of 50 securing them in properly spaced relation for assembly in the casing and also to provide guiding throats or means from one pocket to another or a row of pockets, thereby facilitating the introduction of the springs. The pocket units can 55

be very quickly formed by the sewing operation. In assembling within the cushions, the pocket units are arranged in spaced relation preferably diagonally as indicated in the drawings with the pocket members in zig-zagged relation, their folded ends being lapped upon the underside of the casing and stitched thereto by zig-zag rows of stitching 12, the stitching being preferably continuous and it may be continuous from one row to another as indicated in Fig. 6. This stitching passes not only through the infolded ends of the pocket members and the casing walls but through the padding, thus permanently securing the padding to the wall and effectively quilting the same—that is, providing a quilt stitching that holds the fibers in their arranged position or prevents the objectionable displacement thereof in use or in the handling and assembling of the unit in a mattress or other cushion structure, the pocket units being arranged in zig-zag spaced relation with their pockets zig-zagged, as stated, providing rows of spring pockets, the pockets of adjacent rows alternating and the pockets of each row connected by central longitudinal passages through which springs may be introduced into the pockets. The passages being central of the pockets permit the walls being distended to allow the introduction of springs of greater diameter than would be possible if the pocket openings were in the sides of the pockets. After the springs are inserted, the side walls of the casing which have been left open for the introduction of springs are closed, thus completing the unit.

With this arrangement, a minimum amount of material is required for forming the pockets. The structure may be rapidly assembled not only in the matter of assembling the fabric parts but the introduction of the springs.

In the embodiment shown in Figs. 9, 10 and 11, metal fasteners or stitches 13 are employed instead of the threads or rows of stitches of the embodiment described. These fasteners or wire stitches also serve to secure the padding simultaneously with the securing of the pocket members.

The pocket members and the casing walls may be very easily and quickly assembled to receive the springs and when padding is employed, this is effectively secured to the casing walls and quilted in the same operation.

My improved cushion structure is very economical in material and may be very easily assembled.

I have illustrated and described my improvements in highly satisfactory embodiments thereof. I have not attempted to illustrate or describe certain adaptations or embodiments which I contemplate as it is believed that this disclosure will enable those skilled in the art to embody or adapt my improvements as may be desired.

Having thus described my invention, what I claim as new and desire to secure by Letters Patent, is:

1. A spring cushion structure comprising top, bottom and side casing walls of burlap having pads of sisal arranged on the outer sides thereof and attached thereto at spaced intervals by engaging tufts of the pad fibers between strands of the burlap, a plurality of pocket units disposed in spaced diagonal relation within the casing and each comprising a plurality of pocket members of burlap connected in spaced relation by strips disposed centrally across the same and stitched thereto, said pocket members having their ends folded upon themselves and stitched in folded relation, the pocket members of the units being arranged in zig-zagged relation and their folded ends being stitched to the top and bottom casing walls by continuous zig-zagged rows of stitches through the casing walls and padding thereon whereby a plurality of rows of spring pockets are provided with the pockets of adjacent rows in alternating relation, the pocket units being so spaced relative to each other as to provide a central longitudinal passage for each row of pockets through which springs may be introduced into the pockets, the said pocket unit attaching stitching constituting quilting and securing means for the padding, and springs arranged in said pockets, the individual springs being separated by said pocket members and said strips.

2. A spring cushion structure comprising top, bottom and side casing walls of burlap having pads of sisal arranged on the outer sides thereof and attached thereto at spaced intervals by engaging tufts of the pad fibers between strands of the burlap, a plurality of pocket units disposed in spaced diagonal relation within the casing and each comprising a plurality of pocket members of burlap connected in spaced relation by strips disposed centrally across the same and stitched thereto, the pocket members of the units being arranged in zig-zagged relation and their ends being stitched to the top and bottom casing walls by stitches through the casing walls and padding thereon whereby a plurality of rows of spring pockets are provided with the pockets of adjacent rows in alternating relation, the pocket units being so spaced relative to each other as to provide a central longitudinal passage for each row of pockets through which springs may be introduced into the pockets, the said pocket unit attaching stitching constituting quilting and securing means for the padding, and springs arranged in said pockets, the individual springs being separated by said pocket members and said strips.

GEORGE A. STACKHOUSE.
